KNITTING MACHINE

Harold E. Houseman, Laconia, N. H., assignor to
 Scott and Williams, Incorporated, Laconia,
 N. H., a corporation of Massachusetts

Application May 12, 1939, Serial No. 273,205

16 Claims. (Cl. 66—140)

This invention relates to a knitting machine, and particularly to mechanism for providing yarn changes in a knitting machine of the circular type.

It is the general object of the present invention to provide striping control means in a knitting machine in which yarn fingers are normally urged into active position by spring means and are adapted to be moved out of active position by thrust rods or the like. In general in such machines, pattern changes have been effected by the use of drums carrying cams adapted to positively actuate thrust rods. Such arrangements offer relatively limited possibilities in the production of striping because of the limited circumferential space available on a cam drum and are obviously far less adaptable for the production of patterns than striping devices in which chains of indefinite lengths may be provided. The fact that the yarn fingers are normally urged into active position by spring means creates some difficulties, inasmuch as yarn changes must be very rapidly made involving a quick removal of yarn fingers from action, and, furthermore, there must be a proper time relationship between the outgoing and incoming yarns in order to provide an overlap to avoid holes in the fabric.

Additionally, the use of drums heretofore has involved complications in the way of changing patterns. The thrust rods which were used were heretofore controlled by ring cams on the main pattern drum in which there were gaps where different fingers were released to feed their yarns. In changing patterns to cause the fingers to be active in a different order, these cams had to be changed so that every one of the multiple yarn fingers that was not wanted in action at each step of the drum had to be held up out of knitting position.

This construction made pattern changing far more complicated than on the type of machine in which fingers were spring retained in their inactive positions after a yarn change until the next one had to occur. In accordance with the present invention, provision is made so that no drum cams are needed to hold fingers out of action. If, for example, there are eight yarn changes in a stocking, eight cams of identical type are distributed around the drum in the paths of the different thrust rod actuators. These may be rearranged very quickly for different yarn changing sequences. If two fingers are to go into action together, two of such identical cams may be positioned on the drum in

corresponding circumferential positions. A single cam not only renders a new finger active, but also takes any previously active fingers out of action, unless one of them is to remain in action simultaneously with the new finger, and also operates the clamp and cutter. This yarn changing system actuated from a cam drum is preferably associated with a chain striping device.

The present invention may be regarded as an improvement on the apparatus described in my Patent No. 2,180,707, to which reference may be made for details of the chain striping mechanism which are not disclosed in detail herein.

The above and other subsidiary objects relating primarily to details of construction will be apparent from the following description, read in conjunction with the accompanying drawings, in which:

Figure 1 is a vertical section showing in fragmentary fashion various parts of the improved striping mechanism with indicated conventional parts of the knitting machine;

Figure 2 is an elevation of a portion of the same; and

Figure 3 is a vertical section similar to Figure 1 showing certain details of the clamping and cutting control means.

The machine to which the invention is shown applied is of the type illustrated in Page Patent 1,627,337, which patent discloses various details of the machine which need not be described herein. The machine comprises a needle cylinder 2 which, in the present instance, is a rotating cylinder, the needle cylinder carrying the usual independent latch needles 4 with which there cooperate the conventional elements of machines of this type. In the present instance, the machine comprises a plurality of yarn fingers 6, assumed to be five in number, each adapted to lead a yarn 8 to the needles, the yarn fingers being pivoted upon a common pin 10 and being individually urged into feeding position by springs 12. The various yarn fingers are arranged to be moved to upright inactive position by means of push bars 14, adapted for dual actuation from cams on a main pattern drum 32 and by striping control devices which, as will be evident hereafter, are similar to those of my Patent No. 2,180,707, mentioned above. The push bars 14 are urged upwardly by strong springs 16 adapted to overcome the efforts of springs 12. A shoulder 18 on each of the bars 14 is engageable with a guiding stop member 20 to limit its upward movement. At the upper limit of its movement each of the push bars will serve to elevate the

corresponding yarn finger to inactive position. The push bars 14 are guided at their lower ends within a conventional type of comb 22. As contrasted with the arrangement in said Page patent and my patent mentioned above, these push bars do not extend downwardly to a sufficient extent to be engaged by cams on the drum 32.

Each of the bars 14 is notched as indicated at 24 to receive the forwardly extending arm 26 of a corresponding actuating lever pivoted on a horizontal pin 28 and having a depending arm 30 adapted to be engaged by any cams occupying a corresponding axial portion of the main cam drum, 32.

Each of the push bars 14 is also provided with a notch above its notch 24 having at its lower end a shoulder 34 and at its upper end a cam portion 36. Corresponding to each of the bars 14 is a detent 38, these detents being located side by side and pivoted upon a common pin 42. Each of them has a rearwardly extending arm 44 urged downwardly by a spring 46 to cause the detent to occupy normally a forward position limited by a stop pin 40 extending across all of the detents.

Pivoted upon the pin 42 is a yoke 48 provided with a transverse element 50 lying in front of the detents as indicated in Figure 2. This yoke 48 is adapted to be rocked by the action of any cam portion 36 upon its transverse element 50 to cause that element to engage the detents 38 to move them rearwardly out of the path of the stop shoulder 34.

Each of the levers comprising arms 26 and 30 has a third rearwardly extending arm 52 which, on its under side is provided with sloping cam surfaces 54 and 56. Corresponding to each of these arms is an actuator 58, the actuators being pivoted upon a transverse pin 60 secured in the upper end of an oscillating bracket 62 pivoted at 64 to the frame and adapted to be oscillated once for each revolution of the needle cylinder by means such as illustrated in my said prior application.

Each of the actuators 58 is provided with an upward extension 66 adapted to engage a transversely movable selector finger 68. Each of the actuators 58 is urged counter-clockwise against a stop pin 70 carried by the yoke 62 by means of an individual spring 74. A stop pin 72 limits clockwise movements of these actuators.

The drum 32 carries cams indicated at 76, 76', 76'', etc., respectively adapted to engage the arms 30 of the various triple armed levers, there being such plurality of each of these as is required to effect the various successive operations of each lever. Each of these cams is provided with surfaces 78, 80 and 82 the purposes of which will be apparent hereafter. The cam drum is stepped about in the direction of the arrow in the usual fashion.

Referring to Figure 3, it will be noted therein that the yoke 48 is provided with a rearwardly extending arm 84 with which is adapted to engage an adjustable screw 86 carried by the lever 88 underlying a pin 90 on a push bar 92, which is urged downwardly by a spring 94 to cause its lower end to engage the cam drum 32 or, possibly, cams thereon. This push bar 92 is adapted to operate clamping and cutting means of conventional type indicated at 98, the clamping and cutting means being adapted to clamp and cut any yarn which is being taken out of action.

The operation of this device may best be considered by taking into account separately the control of the yarn fingers by the cams on the

drum 32, the control of the yarn fingers by the chain striping means comprising the elements carried by the bracket 62, and the clamp and cutter operating means.

Referring first to the operations due to the cams on the drum 32, Figure 1 illustrates the position of a push bar 14 when its corresponding yarn finger 6 is active. Under such conditions, the push bar will be slightly spaced from its finger as illustrated and will be held against upward movement under the action of spring 16 by engagement of its detent 38 with its shoulder 34. At such time, the other push bars corresponding to yarn fingers which are inactive will be in upper position having their shoulders 18 engaging stop 20 and accordingly holding their corresponding yarn fingers raised. The detents 38 of such push bars will be resting against their edges below the shoulders 34. The transverse member 50 will at this time lie in the lower portion of the notch below the cam surface 36 of the active push bar 14.

When a change is to be made to another of the yarns, the corresponding push bar is engaged by a cam 76 and the change takes place in a series of steps. As the follower arm 30 corresponding to the yarn finger which is going into action rides upon the surface 78 of a cam 76, the push bar 14 is lowered to a sufficient extent to clear its yarn finger, and consequently the new yarn immediately goes into action. At this time, the downward movement of the corresponding push bar will not be sufficient to cause the cam 36 to move the yoke 48 to disengage the detent 38 from the push bar which has been heretofore removed from its yarn finger which has been in operative position. Thus there is provided a suitable overlap of the ingoing and outgoing yarns.

A continuous movement of the cam 76, however, almost immediately causes the cam surface 80 to move the member 26 still further. Since the push bar of the yarn going into action has already cleared its yarn finger, no further action on this yarn finger takes place. However, the cam 36 of the bar which is being lowered now swings the yoke to such extent as to disengage any detent or detents 38 from their corresponding shoulders 34. Thus the push bars, with the exception of the one which is being lowered, will be released to snap their yarn fingers out of action by the effort of springs 16, which are substantially stronger than the springs 12, tending to hold the yarn fingers in active position.

The movement of cam 76 continues still further, so that the arm 30 will drop upon the portion 82 of the cam 76. This action is sufficient to permit the cam 36 of the lowered bar to rise so that yoke 48 is released and the detents 38 may move counterclockwise under the action of their springs 46. The detent corresponding to the push bar which was lowered then moves above its shoulder 34. As the cam 76 advances to the final position of its step movement, the arm 30 is completely released and the push bar may rise slightly so that its shoulder 34 engages the detent 38. Thus all the parts are rendered ready for a subsequent substitution of yarn fingers.

All of the above described actions occur in a rapid single advance of the drum 32 and the various actions follow in rapid sequence, the action being so rapid that in general only a small, though definite, overlap of the ingoing and outgoing yarns will take place.

Passing now to the operation of the chain striping means, reference may be made for details of the operation of the selecting mechanism to my Patent No. 2,180,707, referred to above. It will be recognized that the devices shown in that patent are of a somewhat more elaborate type than is necessary in the present mechanism. It will be sufficient to state that the selector member 68 is moved parallel to the axis indicated at 64 so as to be positioned by a pattern chain behind any one of the members 58. As the bracket 62 rocks rearwardly, the upper portion 66 of a member 58 will be engaged by the selector 68 so that its end 58 will drop into contact with the end of the arm 52. The arm 52 cannot yield due to the action of the shoulder 18 on bar 14 stopping against 20 but, as pointed out in my said patent, the selector 68 is yieldable against its strong spring and consequently as rearward movement of the bracket proceeds, the member 58 will ultimately ride off the end of the arm 52 and will then snap to a position lower than the end of that arm, the spring controlling the selector 68 causing such lowering action.

Forward movement of the bracket then occurs. The member 58 will now be backed up by the stop 72 and as it moves forward, will successively engage the sloping surfaces 54 and 56 of the lever 52 imparting to it the same steps of movement as were imparted by the cam surfaces 78 and 80. By such action, a change of yarns is effected in the same fashion as by the cam 76.

As the bracket 62 then moves rearwardly, successive release of the three-armed lever takes place, effecting the releasing steps similar to those occasioned by the presence of the cam surface 82. Prior to this rearward movement, the selector 68 will have moved to a neutral position in which it will not engage any of the other members 58, and consequently the spring 74 will raise the member which has just been operative to an upper inactive position against the stop 70. If an immediate yarn change is to be effected, it is, of course, possible that another member will be lowered to effect a yarn change in the next forward movement of the bracket 62.

It will be evident from the above that the three-armed member which effects the yarn changes may be independently actuated by either the cams on the drum 32 or through a suitable pattern chain controlling the selector 68.

At the occurrence of each yarn change, clamping and cutting of the yarn going out of action takes place. This result is achieved by the devices illustrated in Figure 3. The rearwardly extending arm 84 of the yoke 48 will be rocked upwardly whenever that yoke is acted upon by the cam 36 of any of the yarn finger push bars. As it moves upwardly, it will engage the adjustable screw 86 of the lever 88, causing this lever to rise, engaging the pin 90 and lifting the push bar 92 which causes a clamping and cutting action of the clamping and cutting mechanism to take place. The adjustment of the screw 86 is such that the clamp and cutter will be opened wide enough to insure release of the ingoing yarn and reception of the outgoing yarn. Release of yoke 84 takes place when the outgoing yarn is well within the clamp and cutter and effects clamping and cutting of it.

In the event that additional yarn fingers are made subject to control not of the type described herein, but of the type disclosed in said Page patent, cams may be provided on the drum 32

for separate actuation of the clamping and cutting devices.

What I claim and desire to protect by Letters Patent is:

1. In a circular knitting machine, a needle cylinder carrying independent needles, a plurality of yarn fingers, spring means for urging said yarn fingers towards their yarn feeding positions, individual controlling elements for said fingers, spring means urging said controlling elements to move their respective fingers from yarn feeding position, and pattern controlled means for selectively positioning said finger controlling elements so that they may allow their respective fingers to feed yarns or may move them out of yarn feeding position.

2. In a circular knitting machine, a needle cylinder carrying independent needles, a plurality of yarn fingers, spring means for urging said yarn fingers toward their yarn feeding positions, individual controlling elements for said fingers, and operating means for said controlling elements, said operating means being arranged to move a controlling element to release its yarn finger to operative position, and to cause the controlling element in the same movement to render inoperative any yarn finger which was previously active.

3. In a circular knitting machine, a needle cylinder carrying independent needles, a plurality of yarn fingers, spring means for urging said yarn fingers toward their yarn feeding positions, individual controlling elements for said fingers, spring means urging said controlling elements to move their respective fingers from yarn feeding position, detent means for restraining said controlling elements from actuation by their spring means, and means arranged to operate a controlling element to allow its corresponding finger to feed yarn, and simultaneously to release a detent restraining a controlling element for a finger previously operative thereby to render said last named finger inoperative.

4. In a circular knitting machine, a needle cylinder carrying independent needles, a plurality of yarn fingers, spring means for urging said yarn fingers toward their yarn feeding positions, individual controlling elements for said fingers, spring means urging said controlling elements to move their respective fingers from yarn feeding position, detent means for restraining said controlling elements from actuation by their spring means, and means arranged to operate a controlling element to allow its corresponding finger to feed yarn, and simultaneously to release a detent restraining a controlling element for a finger previously operative thereby to render said last named finger inoperative, said last named means effecting the successive positioning of a new finger and removal of a previously active finger to effect overlap of the yarns fed thereby.

5. In a circular knitting machine, a needle cylinder carrying independent needles, a plurality of yarn fingers, spring means for urging said yarn fingers toward their yarn feeding positions, yarn finger operating means arranged to release a finger which is to become active to feed its yarn and to elevate into non-feeding position a finger which has previously been active, clamping and cutting means arranged to clamp and cut a yarn which is being rendered inactive, means for operating said clamping and cutting means, and means operative from a single pattern cam to

effect a change of yarn and clamping and cutting of the yarn which is moved out of action.

6. In a circular knitting machine, a needle cylinder carrying independent needles, a plurality of yarn fingers, spring means for urging said yarn fingers toward their yarn feeding positions, yarn finger operating means arranged to release a finger which is to become active to feed its yarn and to move into non-feeding position a finger which has previously been active, clamping and cutting means arranged to clamp and cut a yarn which is being rendered inactive, means for operating said clamping and cutting means, a striping device comprising selective operators, and means operable by a single selected operator to effect a change of yarn and clamping and cutting of a yarn which is moved out of action.

7. In a circular knitting machine, a needle cylinder carrying independent needles, a plurality of yarn fingers, spring means for urging said yarn fingers toward their yarn feeding positions, yarn finger operating means arranged to release a finger which is to become active to feed its yarn and to move into non-feeding position a finger which has previously been active, clamping and cutting means arranged to clamp and cut a yarn which is being rendered inactive, means for operating said clamping and cutting means, a pattern device, striping means comprising a plurality of selective operators, and means operable selectively either by a single cam on said pattern device or by a selected operator to effect a change of yarn and clamping and cutting of a yarn which is moved out of action.

8. In a circular knitting machine, a needle cylinder carrying independent needles, a plurality of yarn fingers, spring means for urging said yarn fingers toward their yarn feeding positions, a plurality of pattern devices, and means selectively operable from a single controlling element of any of said pattern devices to effect a change of yarn.

9. In a circular knitting machine, a needle cylinder carrying independent needles, a plurality of yarn fingers, spring means for urging said yarn fingers toward their yarn feeding positions, individual controlling elements for said fingers, spring means urging said controlling elements to move their respective fingers from 50 yarn feeding position, and detents for restraining said controlling elements from motion under the action of their spring means.

10. In a circular knitting machine, a needle cylinder carrying independent needles, a plurality of yarn fingers, spring means for urging said yarn fingers toward their yarn feeding positions, individual controlling elements for said fingers, spring means urging said controlling elements to move their respective fingers from 60 yarn feeding position, detents for restraining said controlling elements from motion under the action of their spring means, and pattern devices for controlling said detents.

11. In a circular knitting machine, a needle cylinder carrying independent needles, a plurality of yarn fingers, spring means for urging said yarn fingers toward their yarn feeding positions, yarn finger operating means arranged to release a finger which is to become active to feed 70 its yarn and to move into non-feeding position a finger which has previously been active, a striping device comprising selective operators, and means operable by a single selective operator to effect substitution of one yarn for another.

12. In a circular knitting machine, a needle cylinder carrying independent needles, a plurality of yarn fingers, spring means for urging said yarn fingers toward their yarn feeding positions, 5 yarn finger operating means arranged to release a finger which is to become active to feed its yarn and to move into non-feeding position a finger which has previously been active, a pattern device, striping means comprising a plurality of 10 selective operators, and means operable selectively either by a single cam on said pattern device or by a selective operator to effect substitution of one yarn for another.

13. In a circular knitting machine, a needle cylinder carrying independent needles, a plurality of yarn fingers, spring means for urging said yarn fingers towards their yarn feeding positions, a pattern device carrying cams, and means for effecting changes of yarn comprising cam 20 followers, one for each yarn finger, engageable by said cams, each of said cams being arranged to effect, through one only of said followers, an insertion of the yarn corresponding to said follower and removal of any other yarn previously 25 active.

14. In a circular knitting machine, a needle cylinder carrying independent needles, a plurality of yarn fingers, spring means for urging said yarn fingers towards their yarn feeding positions, a pattern device, a plurality of series of cams on said pattern device, the cams of the 30 various series being variously positioned depending upon the sequence in which yarn fingers are to be rendered active, and followers arranged to be operated by said cams to effect yarn changes, each follower being arranged to be acted upon by cams of one series only, and each complete yarn change being performed solely by the action of one cam upon the one follower belonging to its series.

15. In a circular knitting machine, a needle cylinder carrying independent needles, a plurality of yarn fingers, spring means for urging said yarn fingers towards their yarn feeding positions, a pattern device, a plurality of series of cams on said pattern device, the cams of the 45 various series being variously positioned depending upon the sequence in which yarn fingers are to be rendered active, and followers individual to the yarn fingers arranged to be operated by said cams to effect yarn changes, each follower being arranged to be acted upon by cams of one series only, and each complete yarn change being performed solely by the action of one cam upon the one follower belonging to its series to render active the finger corresponding to said follower and to render inactive any other previously active yarn finger.

16. In a circular knitting machine, a needle cylinder carrying independent needles, a plurality of yarn fingers, spring means for urging said yarn fingers towards their yarn feeding positions, clamping and cutting means for the 60 yarns, a pattern device carrying cams, and means for effecting changes of yarn comprising cam followers, one for each yarn finger, engageable by said cams, each of said cams being arranged to effect, through one only of said followers, an insertion of the yarn corresponding to said follower and removal of any other yarn previously active, and the operation of said clamping and cutting means on the yarn being removed.
